INTRODUCING MERCURY INTO VACUUM
DEVICES

Edmund A. Reuter, East Orange, N. J., assignor to
Westinghouse Electric & Manufacturing Com-
pany, East Pittsburgh, Pa., a corporation of
Pennsylvania

Application June 21, 1941, Serial No. 399,059

7 Claims. (Cl. 250—27.5)

My invention relates to discharge devices, and especially to introducing mercury or other gaseous vapor into the container of such discharge devices.

An object of the invention is to introduce a predetermined amount of mercury or other gaseous medium into a discharge device. Heretofore, the required amount of mercury has been distilled into discharge devices, such as lamps and electronic devices during manufacture or an excess of mercury has been introduced into the lamp and the excess boiled out until the required amount is left.

My invention is a means of introducing a measured amount of mercury into a lamp or electronic device without the disadvantages of these older methods.

In particular, I incorporate the mercury or other gaseous medium in a sealed container inserted in the assembled tube and then release the mercury or other vapor by the use of high frequency after the tube has been pumped out and sealed off.

In particular, my invention permits the ready release of the mercury at the desired time and my preferred embodiment prevents any contamination of air in the mercury introduced into the tube.

Other objects and advantages of my invention will be apparent from the following description and drawing in which:

Fig. 1 is a partial view of one end of a sterilizing lamp in which a preferred embodiment of my invention has been incorporated.

Fig. 2 is an enlarged view of the mercury container illustrated in Fig. 1.

Fig. 3 is a cross sectional view on lines III—III of Fig. 2.

Fig. 4 is a longitudinal cross section of one end of the mercury container of Fig. 2.

Fig. 5 is a modification of the form of container illustrated in Fig. 2.

Figs. 6 through 12 are respectively still further modifications of my invention.

In Fig. 1 I have illustrated one end of a sterilizing lamp to which my invention has been applied. This lamp includes a glass casing 10 having a press 11 at one end through which extends the conductor 12 to the electrode 13. A conductor 16 is connected to a standard 17 coated with glass insulation 18 and passes upward to an electrode, not shown, but similar to 13 and cooperating therewith.

In order to introduce the mercury into the device at the proper time, I provide a container 20

which is more fully illustrated in Fig. 2. This container is welded to a rod 21 welded in turn to one of the fins 22 at the base of the electrode 13. The mercury container 20 is preferably supported adjacent the press 11, where it can be conveniently flashed by a high frequency coil 23 surrounding the tube at the location of the mercury container 20.

The mercury container 20 is a length of seamless metal tube, preferably nickel, with an outside diameter preferably of 25 to 30 mils, and a wall thickness of approximately 3 to 5 mils. The outside diameter is preferably not over 35 mils. The tubing is filled with pure mercury and with the desired quantity determined by the length of the tube. The two ends 25 and 26 of the nickel tubing, are welded shut which produces a flat portion at the end, and the tube is then formed into a circle on a suitable mandrel and the ends welded together, as disclosed in Fig. 2.

This welding operation can be done either as a separate operation, or at the time the ring is welded to the support wire or conductor 21. The small diameter tubing utilized in the preferred dimensions provide a simple operation in making a completely tight weld across the flattened end. Because of the thin wall of the tube and the fact that it is formed into a ring, it is very simple to heat the container 20 by means of the high frequency coil 23 to burst the tube in the finished device.

The tube in the assembly has been completely filled with mercury by means of a vacuum and accordingly there is no danger of contamination of the discharge device because there is no air or a minimum of air included in the mercury. The mercury being extended throughout the ring with a very tiny mass per unit of length prevents the formation of any large globule of mercury flying against the glass wall of the container and breaking it upon the rupture of the tiny ring 20.

The preferred dimensions provide for approximately 60 mg. of mercury in each inch of length of the tubing, and accordingly the mercury dosage for the device can be very accurately determined by the length of the sealed off tube.

In case a larger amount of mercury is desired, I preferably utilize a longer length of tubing, but in this case form the major part into a helical coil 27 illustrated in Fig. 5 and then weld the two ends together at 28.

In some cases, it may be desired to include both mercury and a gaseous medium in the device. For this purpose I provide a small glass tubing 55 or container 30 illustrated in Fig. 6, and include

in this container the gaseous medium in the interior 31 together with the measured amount of mercury 32 and a metal shot or slug 33. At one end of the container I preferably heat up a small area and blow it into the container to form a very thin re-entrant window 34. This container 30 may be attached to any convenient portion of the interior structure of the assembled lamp or electronic device such as the press 11. When the device is jarred, the shot or slug 33 will be driven against the thin window 34 and break it to release the gaseous medium 31 and the mercury 32 into the tube.

In Fig. 7 I have illustrated a further modification of Fig. 6 in which the gaseous medium has been enclosed in the container wall 35 together with the mercury 36. Also in this container is a high expansion wire 37 anchored into the wall and then extended in a straight wire 38 substantially to the opposite wall and then coiled back on itself in a spring 39, reaching back to the anchor place 40 of the wire. The coil will be heated by the high frequency device illustrated at 23 in Fig. 1 and will expand enough to break the wall 35 of the container and then release the mercury and gaseous medium into the device.

Fig. 8 is a still further modification in which the powerful hairpin spring 41 is so shaped that in the open position the points are wider than the largest diameter of the enclosing glass bulb 42. Before inserting into this bulb, the points are put under compression and held by a fusible length or loop of fusible wire 43. When the length is heated by high frequency it melts and releases the spring which breaks the bulb and, in turn, releases the mercury 44 and other desired gaseous medium included in the bulb 42.

Fig. 9 is a still further modification in which a coil spring 45 is put under compression and held by a fusible wire 46 in a shell 47. When the length 46 is melted by high frequency, the spring 45 will be released and fly out of the shell with sufficient force to break the glass bulb container 48.

In Figure 10 I have illustrated merely the glass bulb 49 with a metal shot 50 and the mercury 51 therein, together with any gaseous medium desired. The device may be shaken vigorously so that the shot breaks the bulb and releases the mercury. This particular form of the invention is, of course, not adapted with discharge devices having a delicate structure.

In Fig. 11 I have disclosed a hairpin bimetal 52 inside the bulb 53. An application of heat or high frequency thereto will force it to break the glass bulb and release the mercury 54 and other gaseous medium inside the bulb.

In Fig. 12 I have illustrated a similar hairpin bimetal 55 but I have also provided a thin interior goose neck extension 56 of the wall which

may be easily broken by the expansion of the bimetal hairpin for the release of the mercury 51.

In Figs. 6 through 12 I have mentioned the combination of mercury and other gaseous medium inside the containers. This other gaseous medium may be any one or combination of noble gases, such as argon, neon, etc. In case only mercury vapor is desired inside the tube, then, of course, only mercury would be inserted in the containers illustrated in Figs. 6 through 12.

Although I have described certain preferred embodiments of my invention, it is apparent that still further modifications may be made therein, and accordingly, I desire only such limitations to be imposed on my invention as are necessitated by the spirit and scope of the following claims.

I claim:

1. A casing for the introduction of mercury into a discharge device comprising an elongated member having an interior longitudinal chamber and having means closing said chamber at spaced parts thereof, said spaced closing means being secured externally with respect to each other.

2. A casing for the introduction of mercury into a discharge device comprising an elongated member having an interior longitudinal chamber and having means closing said chamber at spaced parts thereof, said spaced closing means being juxtaposed one on another and rigidly secured together.

3. A casing for the introduction of mercury into a discharge device comprising an elongated member having an outside diameter of from 15 to 35 mils and a wall thickness of 3 to 6 mils, the ends of said casing being closed and secured to each other.

4. A casing for the introduction of mercury into a discharge device comprising a tubular casing having flattened ends, said casing being bent into a loop with said flattened ends thereby brought together and secured to each other.

5. A casing for the introduction of mercury into a discharge device comprising a tubular casing having flattened portions next opposite ends of said casing, said flattened portions of opposite ends being secured together.

6. A casing for the introduction of mercury into a discharge device comprising a tubular casing having a wall thickness of 3 to 6 mils and having flattened ends, said casing being looped with the ends thereof juxtaposed and secured to each other.

7. An evacuated discharged device having electrodes therein, a tubular container having its ends secured to each other, mercury within said container, said container being supported from one of said electrodes.
